UNITED STATES PATENT OFFICE.

EZRA T. GILLILAND, OF NEW YORK, N. Y., ASSIGNOR TO THE EDISON PHONOGRAPH COMPANY, OF ORANGE, NEW JERSEY.

PHONOGRAPH.

SPECIFICATION forming part of Letters Patent No. 393,640, dated November 27, 1888.

Application filed June 7, 1888. Serial No. 276,393. (No model.)

To all whom it may concern:

Be it known that I, EZRA T. GILLILAND, a citizen of the United States, residing at New York city, in the county and State of New York, have invented a certain new and useful Improvement in Phonographs, of which the following is a specification.

My invention relates to details of construction of the Edison phonograph, whereby it is made more convenient and efficient.

In the accompanying drawings, forming a part hereof, Figure 1 is a top view of the principal parts of the phonograph illustrating my invention. Fig. 2 is a side view illustrating the gravity guide-arm. Fig. 3 is a sectional view on line 3 3, Fig. 2. Fig. 4 is a side view illustrating the key-movement for raising the spectacles and setting them back, and Fig. 5 is a top view of the key-movement.

20 A is the main shaft of the phonograph, driven from a suitable motor, operated by hand or power, connected to the shaft by the wheel a. This shaft is mounted in bearings b b' upon a suitable base, A'. Upon the end of the shaft 25 A, and overhanging the bearings, is the phonogram-cylinder B. Mounted on the base in the rear of the shaft A and phonogram-cylinder B is a stationary rod, C, arranged parallel with the shaft A, and carrying a sleeve, D, which 30 is adapted to slide and turn on the rod C. At one end this sleeve D has secured to it the rocking holding-arm E, which rises over the phonogram-cylinder, and has pivoted to its upper end the spectacle-frame F, having two 35 eyes for receiving the recorder and reproducer, as will be well understood. This frame F is turned by the thumb-piece c so as to bring either eye over the phonogram-cylinder. An arm, d, projecting from the rocking holding- 40 arm E laterally, carries at its end an adjusting-screw, e, which bears against the frame F, and is adapted by its adjustment to vary the lateral position of the eye of the frame F, which carries the reproducer, so that the reproducing-needle will be brought into the track of the record. Heretofore the frame F has been held in place by the friction of a spring-washer, so that it would remain in any position to which it was adjusted. This enabled the 45 screw e to be adjusted forward, pushing the frame ahead of it; but when adjusted back-

ward the frame would not follow the screw, and consequently the frame had to be kept pushed back against the screw by hand. To make this adjustment more convenient, it 55 is desirable that the frame F should follow the screw e when adjusted in either direction. To accomplish this I provide the hub of the frame F with triangular notches f, into which takes the beveled point of the spring-pin g, carried 60 by the rocking holding-arm. It will be seen that this spring-pin seeks the bottom of the notch f, and will throw the frame F by its spring-pressure in either direction, to accomplish this, for a limited distance. Hence, when 65 the spectacle-frame is thrown into the position shown in Fig. 1, the screw e can be adjusted backward and forward and the frame F will follow the screw. Since this adjustment is required only for the reproducer, one arm, d, 70 alone is used. It is evident, also, that only one of the notches f need have inclined sides, since adjustment takes place only at one of such notches. This spring adjustment of the spectacle-frame is one of the features of my invention. 75

As will be understood, the spectacle-frame has two fingers, h, provided with adjusting-screws h', which bear upon the stationary guide-rest G, arranged in front of the phonogram-cylinder and parallel thereto. It will be also understood that the shaft A is cut with a fine screw-thread between the bearings b b', which screw-thread feeds forward the rocking holding-arm either for recording or reproducing. Attached to the sleeve D at the end opposite to the rocking holding-arm E is an arm, H. This arm H is secured rigidly to the sleeve D, while another arm, I, is pivoted upon the sleeve D by the side of the arm H and projects beyond the arm H over the shaft A, it carrying above such shaft a section of a nut or guide-block, i, which engages with the screw-thread of the shaft A when the arm I is lowered for that purpose. The arm I passes between the sides of a stirrup, j, into which the end of the arm H is formed. Two set screws, j' j'', pass through the sides of the stirrup j and bear against the sides of the arm I which play between them, thus fixing precisely the lateral 95 position of the arm I. A limited vertical motion is permitted the arm I independent of the 100

arm H, the upward independent motion of the arm I being limited by the pin or screw j^3 , attached to the stirrup j , while the rubber band j' encircles the lower part of the stirrup j , so that the arm I in striking the bottom of the stirrup will be cushioned. The arm I projects forward beyond the shaft A and extends over another screw-threaded shaft, J, which is provided with a screw-thread ent in the reverse direction to the thread of the shaft A and of much greater pitch. This shaft J is mounted upon the base A' in front of the shaft A and parallel therewith, it being driven from the shaft A by a small endless belt, L. Upon the outer end of the arm I is mounted a weighted lever, K, having a hook, k' , with a knife-edge for engaging the screw-thread of the shaft J from the under side, and provided with a knife edge projection, k^2 , which is adapted to ride upon the top of the shaft J and engage with its screw-thread.

It will be seen that the spectacle-frame F is capable of vertical adjustment by the turning of screw h' , and that although the rocking holding-arm E and the arm H are moved to a similar extent, yet the arm I will maintain its connection with the feed-screw of the shaft A, so that the recorder or reproducer can be adjusted more or less into contact with the surface of the phonogram-blank without disturbing the connection of the arm I with the feed-screw. This connection of the arm I with the feed-screw is maintained by gravity, such arm being kept down by its own weight. This has been done heretofore by means of a spring pressing downwardly on the arm I and upwardly on the arm H. But it will be observed that the effect of such a spring is to tend to throw the arm H upwardly and to lift the recorder or reproducer more or less off of the surface of the phonogram-blank. By the substitution of the gravity guide-arm I overcame this tendency and effectually remove an objection to the construction heretofore employed.

It will be seen that when the weighted lever K is in the position shown in the full lines in Fig. 2 the projection k^2 will rest on the shaft J, while the guide-block i will be out of contact with the screw-thread of the shaft A; and since the screw-thread of the shaft J is one of much greater pitch than that of the shaft A the rocking holding-arm of the spectacle-frame will be moved backward with a greater speed than the forward movement of the machine. I provide the machine with this device for the purpose of enabling the surface of the phonogram-blank to be more rapidly turned off by means of the cutting-tool. Heretofore such cutting-tool has been used in connection with the slower thread of the shaft A and with the forward movement. By swinging the lever K into the position shown in dotted lines in Fig. 2 the knife-point k' will be brought under the shaft J. When the lever K is in this position, the arm I falls by gravity until the guide-block i engages the

thread of the shaft A; but by lifting the arm I, which is done in the manner to be presently explained, the guide-block i will be first disengaged from the screw-thread of the shaft A, which will stop the feed movement, and a further upward movement of the arm I will throw the hook k' into connection with the screw thread of the shaft J, when the arm I will be moved with greater rapidity in the reverse direction. To accomplish this lifting movement I provide a lifting-bar, L, which is placed in front of the guide rest G and close thereto. This lifting-bar is attached to a lever, L' , which is pivoted on an arm, L^2 , projecting from the base-frame A'. The lever L' has a key, l , at its outer end, by which its outer end can be depressed, thus raising the bar L and lifting the spectacle-frame, since such bar in being raised strikes one of the fingers h , attached to the spectacle-frame. The spring l' draws the bar L downwardly. Upon the lever L' is pivoted an auxiliary lever, L^3 , thrown upwardly by the spring l' . This lever L^3 has a key, l^3 , and a downwardly-projecting finger, l^3 . The arm L^3 projects downwardly from a point where the lever L' is pivoted to it under the finger l^3 of the auxiliary lever L^3 , where it is provided with a raised stop, l^3 , and in the rear of such stop with a set-screw, l^3 . The lever L^3 , being pivoted upon the lever L' , is capable of a limited vertical motion independent of the lever L' , which movement is limited by the pin l^3 . Now the lever L' may be depressed either at the key l or at the key l^3 . If the key l is depressed, the finger l^3 will strike the stop l^3 , limiting the downward movement of the key and raising the spectacle-frame just sufficiently to disengage the guide-block i from the screw-thread of the shaft A, but not sufficiently to engage the hook k' with the thread of the shaft J. When the parts are in this position, the guide-arm I not being connected with either screw-thread, the spectacle-frame is not fed forward or backward. When, however, it is desired to retract the spectacle-frame, as in going back to repeat some matter with a reproducer which is not perfectly understood, the key l^3 is depressed. The first effect of this is to throw the auxiliary lever L^3 down until it strikes the pin l^3 . This throws the finger l^3 to the rear. The further downward movement carries the lever L' with the lever L^3 . The finger l^3 , however, does not now strike the stop l^3 , but does strike the point of the screw l^3 . This permits of a further downward movement of the parts than is accomplished when the finger l^3 strikes the stop l^3 , the bar L is thrown to a definite extent higher up, and the arm I is lifted so as to bring the hook k' into engagement with the thread of the shaft J, thus retracting the parts rapidly.

It will be understood that the levers L' and L^3 may also be connected by cords with treads. The scale, which has heretofore been placed upon the guide-rest, can now be placed upon the lifting-bar L. Instead of a back-stop which is

struck by the rocking holding-arm E when the spectacle-frame is thrown backward, I provide a finger, m , projecting rearwardly from the arm H, and surrounded by a rubber band, m' , which 5 strikes the edge of the base-frame A' and limits the extent to which the spectacle-frame can be thrown over backward.

What I claim as my invention is—

1. In a phonograph, the combination, with a reproducer mounted upon a laterally-swinging frame, of a spring tending to throw such frame in either direction, and an adjusting-screw for adjusting said frame laterally against the tension of said spring, substantially as set forth.
- 15 2. In a phonograph, the combination, with the swinging spectacle-frame, of a spring throwing such frame to a limited extent in either direction, and an adjusting-screw for adjusting the lateral position of such frame 20 against such spring, substantially as set forth.
- 25 3. In a phonograph, the combination, with the rocking holding-arm and the swinging spectacle-frame pivoted thereon and having inclined notches, of a spring-catch with beveled end engaging such notches, and an adjusting-screw for adjusting the frame laterally, substantially as set forth.
- 30 4. In a phonograph, the combination, with the rocking holding-arm, of a feed-screw and a gravity guide-arm having a loose connection with the rocking holding-arm, substantially as set forth.
- 35 5. In a phonograph, the combination, with the rocking holding-arm, of a feed-screw, a gravity guiding-arm loosely connected with the rocking holding-arm, and adjusting-screws, between which said guide-arm plays, for determining its lateral position, substantially as set forth.
- 40 6. In a phonograph, the combination, with the carrying-sleeve, of the rocking holding-arm attached thereto, an arm fixed to said sleeve and having a stirrup at its end, and the guide-arm pivoted to the sleeve and passing through said stirrup, and having a limited vertical movement in said stirrup independent of said fixed arm, substantially as set forth.

7. In a phonograph, the combination, with the rocking carrying-sleeve, the guide-arm, and the feed-screw, of a retracting-screw and a hook carried by said guide-arm and engaging the under side of said retracting-screw, substantially as set forth. 50

8. In a phonograph, the combination, with the rocking carrying-sleeve, the guide-arm, and the feed-screw, of a retracting-screw and a pivoted lever carried by the guide-arm, having a hook adapted to engage the under side of the retracting-screw, and a finger adapted to engage the upper side of the retracting-screw, substantially as set forth. 55

9. In a phonograph, the combination, with the recorder and reproducer carried by the rocking holding-arm and traveling lengthwise of the phonogram-cylinder, of a lifting-bar having a length equal to the movement of the recorder or reproducer, and a lever moving such lifting-bar to raise the recorder or reproducer off of the surface of the phonogram-blank, substantially as set forth. 65

10. In a phonograph, the combination, with the lifting-bar, of a lever for moving such bar, a stop for limiting the movement, and a moving piece for shifting the stop so as to vary the extent of movement, substantially as set forth. 70

11. In a phonograph, the combination, with the lifting-bar, the lever for moving such bar, and a stop for limiting the movement, of an auxiliary lever mounted on the first lever and having a limited movement thereon, and adapted to change by its movement the point at which the stop will arrest the movement of the levers and lifting-bar, substantially as set forth. 80

12. In a phonograph, the combination, with the lifting-bar, of the levers $L' L^3$, stop l^5 , finger l^4 , and the adjusting-screw l^6 , substantially as set forth. 85

This specification signed and witnessed this 29th day of May, 1888.
